Inventor.

John H. Haldeman.
By his Attorney Allen Webster.

UNITED STATES PATENT OFFICE.

JOHN H. HALDEMAN, OF WESTFIELD, MASSACHUSETTS.

ISOTHERMAL DAMPER.

SPECIFICATION forming part of Letters Patent No. 391,844, dated October 30, 1888.

Application filed March 31, 1887. Serial No. 233,105. (No model.)

To all whom it may concern:

Be it known that I, JOHN H. HALDEMAN, a citizen of the United States of America, residing in Westfield, in the county of Hampden and State of Massachusetts, have invented new and useful Improvements in Isothermal Dampers, of which the following is a specification, reference being had to the accompanying drawings and letters of reference marked *o* thereon.

The object of my invention is to provide a removable device for stoves which shall be compact and complete in itself and of simple and cheap construction, and which shall be free from the objections which obtain against a damper wherein a curved expansion-rod is used; and to that end my invention consists in a plate or stove-lid having attached to it a movable plate and a straight expansion-rod *o* fixed at one end to the plate or lid and extended across the face of the plate or lid, with its free end connected by means of one or more levers to the movable plate, whereby the same is caused to move by the expansion or contraction of the expansion-rod; and, further, it consists in the general construction and arrangement herein set out, whereby the objects of my invention are attained.

In the accompanying drawings, in which like letters of reference indicate like parts, Figure 1 is a top view of a stove-cover having my device applied thereto. Fig. 2 is a view of the same inverted. Fig. 3 is a view of a modification. Fig. 4 is a view of my device *o* as applied to a stove-pipe damper. Figs. 5 and 6 are views of detached parts of the device, and Fig. 7 is an under side view of the part of the stove-lid *a* between lines *xx* of Fig. 2.

Referring to the drawings in detail, *a* indicates a stove-lid having openings *b*. *c* indicates a plate centrally pivoted to the under side of the lid and having openings *j*. *d* indicates a strip of metal which expands when heated and contracts when cold. *e* indicates a bell-crank lever pivoted to the stove-lid. *f* indicates a plate as usually used for a stove-pipe damper, and *g*, *h*, and *i* indicate levers for the purpose of increasing the motion.

The construction will be seen to be simple and inexpensive, and although I have illustrated the application of my invention to a

stove-lid and stove-pipe damper only, it will readily be seen that the same mechanism may be applied in other ways and to other uses *o* than to stove-lids and stove-pipe dampers.

The construction of the device as applied to a stove-lid is as follows: A lid, *a*, of the common shape, is provided with openings *b*, of any convenient shape, and a plate, *c*, is provided with openings to correspond to those in the lid, leaving metal, of course, sufficient to cover the openings in the lid; or radial arms may be used instead of the plate, they being attached to the central pivoted portion of the device. The plate is pivoted to the center of the under side of the lid, and a brass rod, *d*, slotted at one end for the purpose of adjustment, is secured at one end to the lid by a nut or set-screw, *k*, and is pivotally connected at its opposite end with the short arm of the bell-crank lever *e*. The lever *e* is pivoted to the lid at or near the elbow of the lever, and the end of the longer arm engages the plate *c* near its pivotal point. The plate is held in place by a nut or set-screw, *l*. If, now, the device be placed upon a heated stove, the rod *d* will expand in the direction of its length, and one end being fastened firmly to the lid its opposite end will cause the short *o* arm of the bell-crank lever *e*, to which it is pivotally attached, to move outwardly, thus causing the end of the long arm of the lever *e* to move to one side of its normal position, thus causing the plate *c*, with which the long *o* arm of the lever *e* engages, to turn on its pivot until the openings in the plate register with the openings in the cover, thus allowing air to enter the fire-box and thus reducing the draft and allowing the fire to die out until the *o* temperature is so reduced that the rod *d* contracts, and, being immovably fastened at *k*, the lever and plate are moved by the contraction in the opposite direction and the openings closed, thus increasing the draft and automatically maintaining the fire at an even temperature.

The pivotal point of connection of the expansion-rod *d* with the bell-crank lever *e* is indicated by the letter *r* in Fig. 7, and of the bell-crank lever *e* with the lid *a* by the letter *s*. The pivotal point of connection of the plate *c* with the lid *a* is indicated by the letter *l*.

The same construction is applied to the

stove-pipe damper, except that the plate *c* and rod and levers are set so that when the damper is turned to a position to close the opening in the pipe the openings in the pivotal plate *c* will register with the openings in the damper-plate *f*, and the application of heat and consequent expansion of the rod *d* will operate to cause the pivotal plate to turn and cover the openings, thus obstructing the draft and operating to check and maintain the fire at the desired point. The rod *d* is slotted at the end at which it is fastened, to enable the same to be adjusted from time to time as circumstances may require.

In some instances the motion imparted by the expansion of the comparatively short rod *d* will not be sufficient to move the damper or covering-plate a sufficient distance. This may occur where the space in which the rod *d* may be located is very limited, or where but slight variation of temperature is had, and consequently but slight expansion and contraction results. In such cases I multiply the motion by attaching the long arm of the bell-crank lever to the short arm of one or more levers and connecting these auxiliary levers by their long arm to the pivotal plate *c*, thus obtaining the requisite movement under very slight variations of temperature. I illustrate one method of accomplishing this in Fig. 3 of the drawings, the long arm of the bell-crank lever *e* being attached to the short arm of a lever, *h*, through the medium of a connecting-rod, *g*. The lever *h* is pivoted to the lid, and an opening, *m*, made in the plate to permit of the pivotal connection without interfering with the motion of the plate. The long arm of the lever *h* is connected with the pivoted plate by a rod, *i*, so that the expansion and contraction of the rod *d* operate to cause the plate to move and open or close the openings in the same manner as before described, though a less variation in temperature is required to obtain the same motion of the plate.

I am aware that a stove-door has heretofore been constructed provided with a swinging door hinged to open away from the stove-door, and provided with an expansion-rod and levers to cause the swinging door to open and to operate a pointer indicating the temperature in the oven, and that a damper has heretofore been made provided with an expansion-rod located above and outside of the damper-plate, which rod operates to open the damper, and the weight of the damper-plate operates to close it, and I make no claim to the construction of such devices. My device differs in detail of construction, method of operation of the parts, and arrangement of the parts.

Of course the shape and location of the parts and shape of the openings may be greatly varied as circumstances may direct.

Having therefore described my invention, what I claim, and desire to secure by Letters Patent, is—

1. An isothermal damper consisting of a circular plate, *a*, having openings and having centrally pivoted thereto a part or plate, *c*, which turns on its pivot in a plane parallel with the face of plate *a*, and a straight expansion-rod fixed at one end to plate *a*, near its outer edge, and extended across the plate near its center, and having its free end connected at a point near the opposite edge of plate *a* with a lever which engages with and operates in the combination to turn the part *c* on its pivot, all in combination, substantially as shown.

2. The combination of a stove-lid having openings through it, a plate, *c*, provided with like openings and centrally pivoted to the under side of the lid to turn on its pivot in a plane parallel with the face of the lid, an expansion-rod, *d*, fixed at one end to the under side of the lid near its outer edge, and a bell-crank lever, *e*, pivoted at or near its elbow to the under side of the lid, the short arm of which lever engages the free end of the expansion-rod and the long arm of which engages the part *c*, substantially as shown.

3. A plate, *a*, having openings, a movable plate, *c*, pivoted thereto and arranged to cover or expose the openings in plate *a*, a straight expansion-rod fixed at one end to plate *a* and extended across plates *a* and *c*, and a lever, *e*, pivoted to plate *a* and having its short arm connected with the free end of the expansion-rod and its long arm engaging plate *c*, whereby the expansion or contraction of the expansion-rod will cause the turning of plate *c* on its pivot, substantially as stated.

4. As an improved article of manufacture, an isothermal damper for regulating drafts in stoves, &c., consisting of the combination of a plate, *a*, provided with openings, a movable plate, *c*, pivoted to plate *a*, a straight expansion-rod, *d*, fixed at one end to plate *a*, and multiplying levers, as *e*, *g*, *h*, and *i*, connecting the free end of the expansion-rod with the movable plate, all the parts being united to and operating on the plate *a*, substantially as shown.

JOHN H. HALDEMAN.
